UNITED STATES PATENT OFFICE

FLORENCE C. BIGGERT, JR., OF CRAFTON, PENNSYLVANIA, ASSIGNOR TO UNITED ENGINEERING & FOUNDRY COMPANY, OF PITTSBURGH, PENNSYLVANIA, A CORPORATION OF PENNSYLVANIA

CLUTCH

Application filed October 25, 1929. Serial No. 402,380.

My invention pertains to clutches and particularly to clutches of what may be called the one-revolution type, that is, clutches adapted to establish a driving connection between elements of a machine and to release such connection after one revolution, or a given part of a revolution, of the machine has taken place. Devices constructed in accordance with my invention have particular usefulness in throwing into operation the cutting members of the flying cutters employed in rolling mill practice for severing strip material while in motion; and the embodiment of my invention described below in detail is illustrated as applied in such connection. Such devices, however, have many other fields of usefulness.

It is an object of my invention to provide a clutch of the above-named character which will be specially reliable and certain in its operation, and which will be durable, simple, and economical both to construct and maintain. And other objects will appear from the following specification and the claims annexed thereto.

By way of example, I have described in the following specification and shown in the accompanying drawings, a form of clutch in which my invention is embodied, the same being applied to a flying cutter of the character described in my copending application Serial No. 402,381, filed October 25, 1929. The invention, however, may be embodied in other forms, and used in other connections, without exceeding the scope thereof as defined in the appended claims.

In the drawings:

Fig. 1 is a side elevation of the flying cutter and clutch;

Fig. 2 is an enlarged partly sectional view of the clutch;

Fig. 3 is a view of the cams, cam contractors and associated parts of the clutch, as seen from the right of Fig. 2; and

Fig. 4 is a perspective view showing the cams.

As stated, the form of clutch herein selected for description and illustration is shown as applied to a flying cutter of the character forming the subject of my copending appli-

cation above referred to. Referring to Fig. 1, such a flying cutter comprises a frame 10 having an anvil roll 11, over which the strip *a* to be severed travels, mounted in suitable bearings in the lower part thereof. A blade holder 12 carrying a blade 13 cooperates with the anvil roll 11 and is mounted in bearings in a block 14 which is reciprocably mounted in suitable ways formed in the frame 10. The blade holder 12 and anvil roll 11 are driven at peripheral speeds which are substantially the same as the linear speed of the strip *a*, so that when the blade holder and anvil roll are moved into cooperative relation with each other the blade 13 will sever the strip during the motion of the latter.

The block 14 has connected to it one end of a lever 15 which is pivoted to the frame 10 and is operated on, at its other end, by a compression spring 16, whereby the block 14 is normally held in an elevated position with the lever 15 engaging, for instance, against a limiting stop 17 formed on the frame 10. In this elevated position of the block 14, the blade 13 is out of operative relation with the anvil roll 11. When it is desired to sever the strip, the block 14 is depressed, against the action of the spring 16, so that the blade 13 will engage the anvil roll 11, during the revolution of these parts, and thereby sever the strip. To effect the downward movement of the block 14, the latter has pivoted thereto a gag plate 18 which, when in the full line position shown in Fig. 1, stands in the path of an abutment 19 which extends downwardly from a cross head 20 reciprocably mounted in the frame 10. The cross head 20 has connected to it the strap of an eccentric 21 mounted on a shaft 22 carried in suitable bearings in the frame 10. This shaft carries a gear 23 which meshes with a second gear 24 of the same diameter, the latter gear being carried by a countershaft 25 which has its bearings in brackets 26 extending from the frame. The shaft 25 has a gearing connection, of an even ratio, with the blade holder 12.

From the above it will be seen that when the gag plate 18 is in the position shown in full lines in Fig. 1, the abutment 19, during

the downward movement of the cross head 20, will engage it and cause the block 14 to be forced downward. When, however, the gag plate is in the dotted line position, it is out of the path of the abutment 19, so that the block 14 remains in its upper position and is not affected by the reciprocations of the cross head 20. In the operation of the machine, the gag plate remains in the dotted line position until such time as it is desired to sever the strip, whereupon the gag plate is moved into the full line position by means now to be described.

The gag plate 18 has secured thereto a lug 27 to which is pivoted one end of a link 28. The other end of the link is provided with a cam contactor 29, and is pivoted between ears 30 formed in the upper end of an actuating lever 31 which is rockably mounted upon a shaft 32 which may be carried by the brackets 26. The cam contactor 29 cooperates with a cam 33 on the counter-shaft 25, the hump 34 of such cam operating to rock the actuating lever 31 in a contra-clockwise direction and cause the link 28 to push the gag plate 18 from its full line into its dotted line position, the extent of the movement being limited by the engagement of an abutment 31a on the actuating lever with a stop 31b secured to a fixed part of the machine, such as one of the brackets 26.

The actuating lever 31 is formed with a bearing for receiving a transversely extending rock shaft 35 to the end of which is secured an armature lever 36. The armature lever is formed at its end with a cam contactor 37 which cooperates with a cam 38 mounted on the shaft 25 beside the cam 34. The cam 38 is formed with a low portion 39, an incline 40 and a raised portion 41, which latter extends through about three-quarters of its periphery. When the low portion 39 of the cam is opposite the contactor 37, the armature lever 36 can be swung from the dotted into the full line position shown in Fig. 3. Thereafter, as the counter-shaft 25 rotates in the direction of the arrow, the contactor will ride up the incline 40, thereby swinging the actuating lever 31 in a clockwise direction and causing the link 28 to pull the gag plate 18 from its dotted into its full line position. Thus the cam 38 operates to move the gag plate 18 to the right while the cam 33 operates to move it to the left.

The armature lever 36 is normally held in the dotted line position shown in Fig. 3 by means of a torsion spring 42 coiled between it and the actuating lever 31. An electromagnet 43 is mounted on a suitable fixed part of the machine, such as one of the brackets 26, and is disposed so that one pole 44 is opposite the armature lever 36; so that when the magnet is energized the armature lever will be drawn, if the position of the high portion 41 of the cam 38 permits, from the dotted line

position into the full line position in which its cam contactor 37 is in operative relation with the cam 38. In order that the cam contactor 37 may remain upon the raised portion 41 of the cam 38 in spite of the action of the spring 42 and of the fact that the electromagnet 43 may be deenergized, the raised portion 41 is formed with a slight taper, and the cam contactor 37 is correspondingly tapered, as indicated at 37a.

The energizing of the electromagnet 43 can be effected automatically, by means, for instance, which are controlled by the movement of the strip *a*. For example, any one of numerous well known switch devices, which may be conveniently actuated by the leading end of the moving strip *a*, may be employed for energizing the magnet and maintaining it energized for the requisite period of time. If, when the magnet is energized, the low portion 39 of the cam 38 is not opposite the contactor 37, such contactor will simply be drawn against the side face of the raised portion 41 of the cam and will remain in such engagement until the lower portion 39 of the cam comes around, whereupon the contactor 37 will snap forward into a position above the low portion 39 of the cam. The magnet 43 will hold the armature lever in this position until the cam 38 has rotated far enough for its raised portion 41 to have engaged the contactor 37, whereafter, because of the tapered shape of the cam portion 41 and the contactor 37, the magnet may be deenergized without danger of the contactor 37 moving out of operative position with respect to the raised cam portion 41.

In order definitely to insure that the contactor 37 of the armature 36 shall be moved out of operative relation with the cam 38 at each revolution of the counter-shaft 25 when the end of the high portion 41 is reached, a face cam 47 is mounted on the counter-shaft 25 adjacent the cam 38, and is formed with a projection 49 adapted to engage the armature lever 36 just before the low portion 39 of the cam 38 comes opposite the contactor 37. The cam projection 49 definitely pushes the armature lever 36 from the full line to the dotted line position shown in Fig. 3, the armature lever being thereafter maintained in such position by the torsion spring 42.

The operation of the clutch is as follows: It being remembered that the countershaft 25 is geared in one-to-one relation with the eccentric shaft 22, the cams are so disposed upon the counter-shaft that the low portion 39 comes opposite the contactor 37 substantially when the cross head 20 is in its uppermost position permitting the gag plate 18 to be swung in beneath the abutment 19. Supposing that the cycle under consideration of the machine is one in which the clutch is to be operated to cause the strip to be severed,

the magnet 43 will be energized at a time when the low portion 39 of the cam 38 is opposite the contactor 37, or, if the magnet 43 is energized somewhat before that time, its 5 energization will be maintained long enough so that the cam contactor 37 will snap in above the low portion 39 of the cam when such low portion comes opposite it. At the time the armature lever is thus drawn forward, so as to move its contactor 37 into the space above the low portion 39 of the cam 38, the gag plate 18 is in its dotted line position. During the rotation of the countershaft 25 in the direction of the arrow, the inclined 10 portion 40 of the cam 38, pushing against the contactor 37, will move the armature lever 36 to the right, thereby rocking the actuating lever 31 in a clockwise direction and pulling the gag plate 18 from its dotted 15 line position into the full line position in which it is in the path of the abutment 19 on the cross head 20. This is the position of the parts shown in Fig. 2. As the countershaft 25 continues to rotate, the tapered edge 20 25 37a of the contactor 37, engaging the tapered face of the cam portion 41, prevents disengagement laterally of the contactor 37 from such cam portion; so that the circuit of the magnet 43 can be broken at any time after 30 the contactor 37 has come into engagement with the tapered edge of the high portion 41 of the cam. During the continued rotation of the countershaft 25, in which time the block 14 descends and ascends, the gag plate 18 is 35 definitely maintained in line with the abutment 19 by the continued engagement of the contactor 37 with the high portion 41 of the cam. When the shaft 25 has rotated through a further distance, sufficient for the block 14 40 to have passed its lowest position, and, in this instance, to have nearly completed its upward movement, the projection 49 of the face cam 48 engages the face of the armature lever 36 and rocks the latter about its pivot, 45 to push the contactor 37 definitely off the high portion 41 of the cam. The high portion 41 of the cam is reduced, as indicated at 50, to enable the contactor 37 thus to be pushed off therefrom. Immediately thereafter, in the further revolution of the countershaft 25, the hump 34 of the cam 33 will engage the contactor 29 on the link 28, whereby the gag plate 18 is pushed back from its full line into its dotted line position in such a 55 definite manner as to overcome any clamping action which may obtain owing to the pressure of the top of the gag plate 18 against the abutment 19 by the spring 16. The gag plate will remain in its dotted line position 60 during any number of further rotations of the shaft 25, thereby enabling the strip a to continue its movement, without being severed, until the magnet 43 is again energized. To prevent accidental movement of the gag 65 plate into position beneath the abutment 19, a spring 51 may be supplied, connected, for instance, between the gag plate 18 and the frame 10.

It will be seen that the device permits of an exceedingly simple and rugged construction, and that it is entirely certain in its operation. When the magnet 43 is energized, the armature lever 36 is moved into position so as to put the device in condition for operation, and this can only occur when the cross head 20 is in a position in which the gag plate 18 can be introduced beneath it. When the gag plate has been swung in below the cross head, so as to cause the block 14 to be depressed, it is definitely held in such position by the engagement of the contactor 37 with the high cam portion 41, such engagement being locked by reason of the tapered shape of these parts. Likewise, on the near completion of the cycle, the armature lever 36 is operated by the cam projection 49, and, later, the gag plate is pushed aside by the cam projection 34, so as to insure definitely that the device be thrown out of operation until the magnet 43 is again energized. By thus providing means whereby the clutch member, in this instance the gag plate 18, is always definitely moved out of operation at each cycle, it is made certain that the cutting operation shall not be accidentally repeated in successive cycles of the machine.

I claim:

1. The combination with a driving element, a driven element, and a movable clutch member for establishing driving connection between said elements of means for actuating said clutch member comprising a cam, a cam-member adapted to be actuated by said cam and movable into and out of operative relation therewith, said cam-member being connected with said clutch member to operate the latter, and an electromagnet for moving said cam-member into operative relation with said cam.
2. The combination with a driving element, a driven element, and a movable clutch member for establishing driving connection between said elements of means for actuating said clutch comprising a shaft, a cam thereon, a cam-member actuated by said cam and movable into and out of operative relation therewith, said cam-member being connected with said clutch member to operate the latter to establish driving connection between said elements, and a second cam on said shaft adapted to operate said clutch member to break such driving connection.
3. The combination with a driving element, a driven element, and a movable clutch member for establishing driving connection between said elements of means for actuating said clutch member comprising a cam, a cam-member adapted to be actuated by said cam and movable into and out of operative relation therewith, said cam-member being connected with said clutch member to operate the latter to establish driving connection between said elements, and a second cam on said shaft adapted to operate said clutch member to break such driving connection.

tion therewith, said cam-member being connected with said clutch member to operate the latter to establish driving connection between said elements, means, operative at each cycle of the actuating means, adapted to operate said clutch member to break such driving connection, an electromagnet for moving said cam-member into operative relation with said first-named cam, and means, operative at each cycle of the actuating means, adapted to move said cam-member out of operative relation with such cam.

4. The combination with a driving element, a driven element, and a movable clutch member for establishing driving connection between said elements of means for actuating said clutch comprising a shaft, a cam thereon, a cam-member actuated by said cam and movable into and out of operative relation therewith, said cam-member being connected with said clutch member to operate the latter to establish driving connection between said elements, a second cam on said shaft for operating said clutch member to break such driving connection, and a third cam on said shaft for moving said cam-member out of operative relation with said first-named cam.

5. The combination with a driving element, a driven element, and a movable clutch member for establishing driving connection between said elements of means for actuating said clutch comprising a shaft, a cam thereon, a cam-member actuated by said cam and movable into and out of operative relation therewith, said cam-member being connected with said clutch member to operate the latter to establish driving connection between said elements, a second cam on said shaft for operating said clutch member to break such driving connection, an electromagnet for moving said cam-member into operative relation with said first-named cam, and a third cam on said shaft for moving said cam-member out of operative relation with such cam.

6. The combination with a driving element, a driven element, and a movable clutch member for establishing driving connection between said elements of means for actuating said clutch member comprising an operating member associated with said clutch member, a cam, a cam-member adapted to be actuated by said cam to move said operating member in one direction, said cam-member being associated with said operating member so as to be movable with respect to the latter into and out of operative relation with said cam, and a second cam for moving said operating member in the opposite direction.

60 7. The combination with a driving element, a driven element, and a movable clutch member for establishing driving connection between said elements of means for actuating said clutch member comprising an operating member associated with said clutch member,

a cam, a cam-member adapted to be actuated by said cam to move said operating member in one direction, said cam-member being associated with said operating member so as to be movable with respect to the latter into and out of operative relation with said cam, a second cam for moving said operating member in the opposite direction, and a third cam for moving said cam-member out of operative relation with said first-named cam.

70 8. The combination with a driving element, a driven element, and a movable clutch member for establishing driving connection between said elements of means for actuating said clutch member comprising a cam-member adapted to operate said clutch-member to establish driving connection between said elements, a cam adapted to actuate said cam-member and having a portion for maintaining the latter in actuated position, means for effecting a relative movement into and out of operative relation between said cam-member and cam, and means for preventing said relative movement during operation of the maintaining portion of said cam.

85 9. The combination with a driving element, a driven element, and a movable clutch member for establishing driving connection between said elements of means for actuating said clutch member comprising a cam-member adapted to operate said clutch-member to establish driving connection between said elements, a cam adapted to actuate said cam-member and having a portion for maintaining the latter in actuated position, and means for effecting a relative movement into and out of operative relation between said cam-member and cam, said cam-member and the maintaining portion of said cam being shaped to prevent relative movement of one out of operative relation with the other.

90 10. The combination with a driving element, a driven element, and a movable clutch member for establishing driving connection between said elements of means for actuating said clutch member comprising normally ineffective means, operable on each cycle of the actuating means, for operating said clutch member to establish driving connection between said elements, means for rendering said operating means effective when operation of said clutch member is desired, and means operable on each cycle of the actuating means adapted to operate said clutch member to break driving connection between said elements.

100 11. The combination with a driving element, a driven element, and a movable clutch member for establishing driving connection between said elements of means for actuating said clutch member comprising normally ineffective means operable on each cycle of the actuating means for operating said clutch member to establish driving connection between said elements, means for rendering said

operating means effective when operation of said clutch member is desired, means operable at each cycle of the actuating means adapted positively to render said operating means ineffective, and means operable on each cycle of the actuating means adapted to operate said clutch member to break driving connection between said elements.

10 In testimony whereof, I sign my name.
